UNITED STATES PATENT OFFICE.

EMMETT HORTON, OF ELMIRA, NEW YORK.

BASKET-HANDLE-FASTENING MACHINE.

1,179,184.

Specification of Letters Patent.

Patented Apr. 11, 1916.

Application filed June 1, 1915. Serial No. 31,511.

To all whom it may concern:

Be it known that I, EMMETT HORTON, a citizen of the United States, residing at Elmira, in the county of Chemung and State of New York, have invented certain new and useful Improvements in Basket-Handle-Fastening Machines, of which the following is a specification.

My invention relates to an improvement 10 in basket-handle fastening machines.

The object of this invention is to provide means for catching and holding the basket, firmly impaling its opposite sides simultaneously upon the sharp points of a wire 15 handle previously positioned for the purpose, and finally in one continuous motion of the machine clenching the ends securely around the rim of the basket, whereby to effect a quick, permanent and rigid fastening 20 of the handle to the basket.

With these objects in view, the invention comprises a solid cast-iron base, means for holding a handle in position to be applied to the basket, a pair of jaws which receive 25 the opposite edges of the basket approximately at the center when operating on a standard grape-basket, means for swinging said jaws positively to cause the ends of the handle to impale opposite sides of the basket, anvils for clenching said ends, and 30 means for applying the required pressure to said anvils.

The invention further consists, in connection with the foregoing elements, of a 35 means of gaging the basket so that the handle is invariably applied approximately at its center.

The invention still further consists in certain mechanical elements for feeding one 40 handle at a time in position, where it is held in readiness to be applied to the basket when the latter is positioned and its sides are being clamped and impaled by the ends, after which the latter are securely 45 clenched.

In the accompanying drawings:—Figure 1 is a top plan view showing a handle in full lines in position to be applied, and the 50 position of the parts of the machine in full lines when the basket is inserted in the machine preparatory to having the handle applied; Fig. 2 is a vertical longitudinal sectional view; Fig. 3 is a view in front elevation; Fig. 4 is a view with the top plate removed showing the parts in the position taken at the completion of the clenching; 55 Fig. 5 is a fragmentary view showing the clenching partly completed; Fig. 6 is a similar view showing the ends of the handle still further clenched; Fig. 7 is a detail showing 60 the completion of the clenching; Fig. 8 is one of the anvils; Fig. 9 is a view of one of the spring-guides for the handles; Fig. 10 is a detached view of one of the rigid plates between which the handles are temporarily wedged and held; Fig. 11 is a detail showing the left-hand handle holder; and Figs. 12 and 13 are detail views showing 65 the end of the plunger 26.

A is the cast-metal base. This is adapted 70 to be bolted to a table or bench, as at 1, 1, through the flanged outer edge 2. The main central portion constitutes a housing and support for the principal working parts of the machine, the opposite sides of the casting being connected across by the integral horizontal bridge 3, on opposite sides of which these working parts are arranged.

A reciprocating-bar 4 has longitudinal 75 sliding connection with the base upon which it is supported, and by which it is guided in its movements, the outer ends being straddled and supported by the studs 5, 5. A pin 6 extends across from these studs and confines the forward end of this bar between 80 it and the lower surface of the bridge 3, as shown in Fig. 3. The ends of a cotter-pin 7 in the bar limit the movement of the latter 85 in one direction. The head of this bar 4 is widened, and is provided with the two cam 90 grooves 8, 8, one on either side of the center, as shown in Figs. 1 and 4, the function of which is to swing and positively control the movement of the two clamping-jaws 9, 9, 95 between the forward bifurcated ends of which the edge of the basket B is held, as shown in Figs. 1, 5, 6 and 7. These clamping-jaws 9 are in the general form illustrated in Fig. 4, they being fulcrumed at or 100 near the center on studs 10, 10, and at their inner ends provided with rollers 11, 11, which travel in cams 8, 8. These cams 8, 8, 105 are in the main parallel, as shown in Fig. 4, although their inner ends extend outwardly, and the jaws are consequently held stationary during the greater part of the movement of the hand-lever 12, they being swung inwardly when the laterally-extending inner ends of the cams 8, 8, reach the rollers 11, 11, in the extreme outer position 110 of the bar 4. The reciprocating bar also has at its head end a pair of upturned lugs 13

and 14, between which the hand-lever 12 is confined, and by which the bar is reciprocated in and out, accordingly as the hand-lever is forced forward or backward, the 5 hand-lever being fulcrumed at one end on the post 15.

The anvils 16, 16, for clenching the ends of the handles are provided with screw-threaded shanks 17 (see Fig. 8) whereby 10 they are screwed into the outer ends of the levers 18, 18. These levers 18 are fulcrumed conveniently on the upper ends of the studs 5, 5, after which, in the neighborhood of the center of the machine, they cross, as the 15 blades of a pair of shears (as shown very clearly in Figs. 1 and 4) and links 20, 20, are pivotally connected to the outer ends of these levers 18 and to each other at the longitudinal center of the machine by means of 20 the pin or rivet 21 at a point between the lugs 13 and 14 in the direct path of the latter, in position to be engaged by one and then the other, the lug 13 to force the anvils outward in the clenching operation, as 25 shown in Figs. 4, 5, 6 and 7, and exert a powerful leverage thereon, and the lug 14 in position to withdraw the anvils and bring them together as shown in Fig. 1, when the hand-lever 12 is swung outward. After the 30 anvils are screwed into the ends the levers, they are held securely in place by set-screws 22, 22. Thus the reciprocating bar 4 has the combined function of swinging and controlling the clamping-jaws which hold the 35 edges of the basket and causing them to be impaled by the ends of the handles, and also the levers which carry the anvils for clenching the ends of the handles to the basket, a powerful and positive leverage being provided 40 for these essential moving parts in this simple manner, namely by the endwise reciprocations of the bar 4 operated by the hand-lever 12.

A face-plate 23 is secured to the base just 45 over the clamping-jaws and anvil-levers by means of the bolts 24, 24. The upper ends of the studs 5, 5, extend into this face-plate, as shown in Fig. 1.

Erected on the face-plate are the two handle-holders 25, 25. These are made of metal 50 bent into the form of an acute angle to conform to and embrace the bends in the sides of the handles. Handles H are stacked vertically in the holders, and they are forced 55 from the holders, one at a time, the bottom-most first by the plunger 26, which is confined between a pair of guides 27, 27, in its movements back and forth, the plunger being operated by the hand-lever 28, which is 60 fulcrumed conveniently on the same post 15 on which the hand-lever 12 is fulcrumed. The plunger 26 rests upon the face-plate, and, as it is forced inward, its grooved projecting forward ends 29 engage the lower- 65 most handle and force it through the slots

30 of the forward side of the handle-holders 25, 25, shown in Fig. 11; and as the plunger 26 tapers a little at the forward end and is a trifle thicker than the handles, as it moves forward it pushes a handle at a time 70 from the holders, and in so doing it lifts all the other handles slightly therefrom.

As the lowermost handle is forced forward, its corners contact with the inner edges of the spring guides 31, 31, shown in 75 Figs. 1, 5, 6, 7 and 9, the springs 32 exerting a slight pressure thereon, and creating a slight resistance to the handles, thus insuring three points of contact, namely at the two sides or corners and the middle, so 80 that they are always fed properly forward, after which they are received between the two handle-holding plates 33, 33, (Figs. 1, 5, 6, 7 and 10), where they are held and supported from the back during the impaling 85 and clenching operation.

A U-shaped guide G is secured to the base to receive the end of the basket, and when the end of the latter is placed in this gage, the center falls opposite the end of the handle. The stops 34, 34, are in position approximately beneath the clamping-jaws, and against these the basket is held. 90

In operation, the levers are normally both thrown to the position shown in Fig. 1, 95 that is to the outermost position where they are not quite but nearly parallel. The operator first pulls the hand-lever 28 toward him, thereby pushing forward a handle into position between the handle-holding plates 33, 33, after which he immediately swings the lever 28 back to its normal position. He now takes a basket, puts one end against the gage G, compressing the center, and slides it into the two clamping-jaws 9, 9, 100 as in Fig. 1. Having thus placed and held the basket, the operator swings the lever 12 toward him, as far as it will go, with a good smart pull. This causes the insertion of the ends of the handles into the basket, and the final clenching of these ends around the basket rim, all of which is shown successively in Figs. 1, 5, 6 and 7. He then 105 swings the hand-lever 12 back to its normal position, and removes the basket which is now completed. This operation is then repeated as many times as it is desired to affix a handle to a basket. 110

I claim:—

1. A basket-handle fastening machine, 115 comprising means between which the handles to be fastened are temporarily held against lateral movement, movable means for positively impaling the sides of the basket upon the ends of the handle thus held, and anvils for clenching said handle-ends. 120

2. A basket-handle fastening machine, 125 comprising means between which the handles to be fastened are temporarily held against outward movement, movable means 130

for impaling the sides of the basket upon the ends of the handle thus held, anvils for clenching said handle-ends, and a single operating lever for actuating said movable means and anvils at timed intervals.

5 3. A basket-handle fastening machine, comprising stationary means and movable means for gripping and impaling the sides of a basket upon the ends of the handle to 10 be affixed thereto, and movable anvils which engage the handle ends and clench them by pressing toward the stationary handle-holding means.

4. A basket-handle fastening machine, 15 comprising a gage, laterally movable clamping-jaws, means for holding the handles while said jaws impale the basket upon the handle ends, and movable anvils acting in opposition to said handle-holding means to 20 clamp the ends of the handles.

5. A basket-handle fastening machine, 25 comprising a gage, laterally movable clamping-jaws, means for holding the handles while said jaws impale the basket upon the handle ends, movable anvils acting in opposition to said handle-holding means to 30 clamp the ends of the handles, and a reciprocating bar having cams which actuate and positively move the clamping-jaws.

35 6. A basket-handle fastening machine, comprising a gage, laterally movable clamping-jaws, means for holding the handles while said jaws impale the basket upon the handle ends, movable anvils acting in opposition to said handle-holding means to 40 clamp the ends of the handles; a reciprocating bar having cams which actuate and positively move the clamping-jaws, and means carried by said reciprocating bar for moving the anvils.

45 7. A basket-handle fastening machine, comprising a gage, laterally movable clamping-jaws, means for holding the handles while said jaws impale the basket upon the handle ends, movable anvils acting in opposition to said handle-holding means to 50 clamp the ends of the handles, a reciprocating bar having cams which actuate and positively move the clamping-jaw, means carried by said reciprocating bar for moving the anvils, and a hand-lever having connection with the reciprocating-bar for moving the latter to actuate the clamping-jaws and anvils.

55 8. In a basket-handle fastening machine, the combination with a base, a reciprocating-bar having sliding connection therewith, said bar having grooves therein, and provided with a pair of lugs, of movable clamping-jaws and movable anvils, both of which are actuated by said reciprocating bar, one by the grooves and the other by the lugs.

60 9. A basket-handle fastening machine, comprising a base, a face-plate, handle-holders erected thereon, a plunger for re-

moving a handle at a time, stationary handle-making plates, and pivoted spring-guides which coöperate with the plunger in guiding a handle at a time between the stationary handle-plates.

70 10. A basket-handle fastening machine, comprising a base, a face-plate, handle-holders erected thereon, a plunger for removing a handle at a time, stationary handle-holding plates, pivoted spring-guides 75 which coöperate with the plunger in guiding a handle at a time between the stationary handle-plates, and movable means for causing the basket to be handled to be impaled upon the ends of the handle held by the handle-holding plates, and movable means for 80 clenching the ends of said handle.

11. A basket-handle fastening machine, comprising a base, a face-plate, handle-holders erected thereon having their lower 85 ends slotted at the forward edge for the escape of a single handle at a time, and a slightly tapered plunger a trifle thicker than the handles and constructed and adapted to push a handle at a time from the holders 90 and in so doing lift the remaining handles away from the lowermost handle.

12. In a basket-handle fastening machine, the combination with a base, a face-plate, handle-holders thereon, a plunger for removing a single handle at a time, of handle-holding plates, movable means for impaling the article to be handled upon the ends of the handles, movable means for clenching the ends of said handles, and two levers fulcrumed at a common point, one connected with the plunger for operating the latter, and the other with the movable means for actuating them.

13. In a basket-handle fastening machine, the combination with a base, of a reciprocating-bar having lugs and cams at one end, an operating hand-lever fulcrumed on the base and passing between said lugs on the reciprocating-bar for actuating the latter, 105 links pivoted together and located between the lugs, crossed anvil-levers fulcrumed on the base and pivotally connected with said links, anvils carried by these levers, and clamping-jaws pivoted to the base and having rollers in the cams of the reciprocating bar, whereby, when the latter moves, the clamping-jaws are actuated.

14. In a basket-handle fastening machine, the combination with a base having 120 a bridge across from side to side, and a face-plate, studs extending through the bridge and face-plate, a cross-pin extending from one stud to the other, of a reciprocating bar slidably connected with the face-plate and 125 between said studs and beneath the bridge, pivotally-mounted clamping jaws, and anvils, said jaws and anvils having connection with and operated by the reciprocating bar, and means for actuating said bar.

15. In a basket-handle fastening machine, the combination with a base having a bridge across from side to side, and a face-plate, studs extending through the bridge and face-plate, a cross-pin extending from one stud to the other, of a reciprocating bar slidably connected with the face-plate and between said studs and beneath the bridge, pivotally-mounted clamping jaws, and an-
5 vils, said jaws and anvils having connection with and operated by the reciprocating bar, means for actuating said bar, and means for supporting a supply of handles, a plunger for feeding a handle at a time, and means
10 between which the handles are wedged for holding the latter while clamping-jaws im-
15 pale the basket upon their ends.
16. A basket-handle fastening machine, comprising means between which the han-
20 dles to be fastened are temporarily held against outward movement, outwardly mov-
able means for impaling the sides of the basket upon the ends of the handle thus held, and outwardly moving anvils for clenching
25 said handle-ends.

17. A basket-handle fastening machine, comprising stationary means between which the handles are held, outwardly movable means for gripping and impaling the sides of a basket upon the ends of the handles, 30 and movable anvils which engage the handle ends and clench them by pressing toward the stationary handle-holding means.

18. A basket-handle fastening machine, comprising means between which the han- 35 dles to be fastened are temporarily held, os-
cillatory means for receiving and embrac-
ing the opposite edges of the basket and
swinging them laterally in opposite direc-
tions whereby to impale them upon the ends 40 of the handles, and means actuated after
the completion of the impaling to engage
and clench the ends of the handles.

In testimony whereof I affix my signature,
in the presence of two witnesses.
